Primary Examiner — Wan Laymon(74) Attorney, Agent, or Firm — Downs Rachlin Martin PLLC(57) CLAIM

The ornamental design for a projector yoke fixture, as shown and described.

DESCRIPTION

FIG. 1 is a perspective view of a projector yoke fixture showing our new design;

FIG. 2 is another perspective view thereof;

FIG. 3 is a front view thereof;

FIG. 4 is a rear view thereof;

FIG. 5 is a side view thereof;

FIG. 6 is a second side view thereof;

FIG. 7 is a top view thereof; and,

FIG. 8 is a bottom view thereof.

The broken lines in the Figures are for the purpose of illustrating unclaimed portions of the projector yoke fixture and form no part of the claimed design. The shade lines in the Figures show contour and not surface ornamentation.
